UNITED STATES PATENT OFFICE.

JOHN J. MARTIN, OF LOS ANGELES, CALIFORNIA.

RAILWAY.

No. 910,559.

Specification of Letters Patent.

Patented Jan. 26, 1909.

Application filed October 22, 1908. Serial No. 459,088.

To all whom it may concern:

Be it known that I, JOHN J. MARTIN, a citizen of the United States, residing at Los Angeles, in the county of Los Angeles and State 5 of California, have invented new and useful Improvements in Railways, of which the following is a specification.

My invention has to do with railways and more particularly to modes of fixing railway

10 rails with respect to their beds; and it contemplates the provision of a railway constructed in such manner that the rails are securely held against vertical and lateral movement and are uniformly supported throughout 15 out their length, thereby assuring a perfect continuous and uniform rolling surface for cars and eliminating the shocks and jars so frequently incidental to the movement of cars or trains.

20 The invention also contemplates providing a railway, designed especially for use in the streets of cities, and constructed with a view of being expeditiously and easily repaired, when the rails are worn or otherwise impaired, at a minimum cost and without entailing material if any injury to the pavement of a street.

25 The invention further contemplates the provision of railway rails of such construction that adequate provision is made for expansion and contraction of the rails, due to changes in temperature, and this without the objectionable creeping and the evils attendant thereon.

30 Other advantageous features peculiar to my novel railway construction will be fully understood from the following description and claims when the same are read in connection with the drawings, accompanying and 35 forming part of this specification, in which:

40 Figure 1 is a plan view of a portion of a railway, constituting the best practical embodiment of my invention of which I am cognizant. Fig. 2 is a transverse section of 45 the same. Fig. 3 is an enlarged detail transverse section showing the relative arrangement of one of the rails and the holder and support thereof. Fig. 4 is a detail view illustrative of the intermediate portion of one of 50 the rails comprised in my improvements.

Similar letters designate corresponding parts in all of the views of the drawings, referring to which:

55 A is the bed of my novel railway, which is formed of plastic material, preferably concrete, and is designed, when the improve-

ments are used in a city, to be laid with its upper side flush with the surface of a pavement. The said bed comprises spaced longitudinal and parallel portions *a*, and a plastic, 60 preferably concrete, connection between the two; the said connection being preferably formed by transverse concrete portions *b*, arranged at suitable intervals apart and made integral or in a homogeneous mass with the 65 longitudinal portions *a*.

B are the rails of the improved railway, and C are the rail-holders and supports, all of which are carried by and extend longitudinally of the longitudinal bed portions *a*. The 70 rails B are peculiar in that they are respectively made up of a head *c* and a web *d* depending therefrom; and the rail holders and supports C each comprise two longitudinal angle irons *e*, spaced apart and embedded in 75 a longitudinal portion *a* of the bed and held against upward movement by the same.

It will be manifest by reference to Figs. 2 and 3 that the longitudinal bed portions *a* constitute durable and staple supports for 80 the rail holders and supports C and preclude casual movement of the same in any direction, and that the holders and supports C, in turn, serve, by reason of the arrangement of their upright parts directly under the heads 85 of the rails, to adequately support and lend strength to the rails, so that a solid and uniform surface is afforded for cars to travel upon, and one which admits of the meeting ends of the rails being opposed to each other 90 obliquely, as shown in Fig. 1, or in any other approved manner without liability of the cars being subjected to shock and jar incidental to the passage of their wheels from one rail to the adjoining one. It will also be 95 manifest that by reason of the rails being detachably connected by bolts D to their respective holders and supports, any rail when worn or otherwise impaired, may be expeditiously and easily removed and replaced by 100 a new rail at a minimum cost, because of the small amount of steel in the rail, and without entailing material, if any injury, to the bed or the pavement in which the same is arranged.

105 I prefer, in the connection of the rails B to the holders and supports C, to employ a plurality of the bolts D; and to provide each of the rail webs with a plurality of transverse apertures, the middle aperture of each series 110 being preferably of circular form, and the others being rectangular in outline and grad-

ually increased in length as they recede from the said circular aperture, as clearly shown in Fig. 4. As will be readily understood, the provision just described is possessed of material advantage, inasmuch as it enables the rails to expand and contract in both directions equally and at the same time precludes the objectionable endwise creeping of the rails.

10 With a view of precluding casual lateral movement or displacement of either of the rails and rail supports and holders, I provide at intervals in the length of the railway the tie rods E, one of which is clearly shown in Fig. 2. Each of the said rods E is embedded in one of the transverse bed portions b and extends through the upright portions of the rail supports and holders and is headed or otherwise secured in approved manner at the outer sides of the said holders and supports. From this it will be understood that the tie rods E reinforce and strengthen the plastic bed and at the same time effectually prevent spreading of the rails, and also prevent the imposing of pressure or strain on either of the longitudinal bed portions a, due to outward pressure exerted against the heads of the rails. It will also be observed that the tie-rods E effect connection between the two angle irons comprised in each holder and support C.

15 It will be gathered from the foregoing that my novel railway is possessed of strength and durability and is calculated to afford a solid and uniform bearing surface for an indefinite period; and that the initial cost of the improved railway is more than offset by the facility with which repairs may be made, and the fact that the removal of an impaired rail and the replacing of the same by a new rail 20 involves but a minimum loss in the cost of material, and does not entail material, if any, injury to either the bed A or the pavement in which the same is arranged, the damaged rail being simply disconnected and lifted from between the upright portions of the holders and supports C, and the web of the new rail being set between the said portions and fastened in the manner shown and described.

25 As before stated herein, the construction shown and described constitutes the best practical embodiment of my invention of which I am aware, but it is obvious that in the future practice of the invention such changes or modifications may be made as fairly fall 30 within the scope of my invention as defined in the claims appended.

Having described my invention, what I claim and desire to secure by Letters-Patent, is:

The combination in a railway, of a plas-

tic bed, a rail holder and support permanently embedded in and held against movement by the bed and extending upwardly beyond the upper side thereof, a rail having a head bearing on the holder and support and also having a web extending downwardly into the same, and a bolt disposed above the bed and extending transversely through and detachably connecting the portion of the holder and support, above the bed, and the web of the rail.

2. The combination in a railway, of longitudinal plastic bed portions, a transverse plastic bed portion extending between and comprised in a homogeneous mass with the longitudinal bed portions, rail holders and supports permanently embedded in and held against movement by the longitudinal bed portions and extending upwardly beyond the uppersides thereof, rails having heads bearing on the holders and supports and also having webs extending downwardly into the same, bolts disposed above the bed and extending transversely through and detachably connecting the portions of the holders and supports, above the bed, and the webs of the rails, and a transverse, metallic tie-rod disposed in and constituting a reinforcement for the transverse plastic bed portion and extending between and connecting the rail holders and supports.

3. The combination in a railway, of longitudinal plastic bed portions, a transverse plastic bed portion extending between and comprised in a homogeneous mass with the longitudinal bed portions, rail holders and supports permanently embedded in and held against movement by the longitudinal bed portions and extending upwardly beyond the uppersides thereof and respectively comprising angle irons separated by intervening spaces, rails having heads bearing on the holders and supports and also having webs extending downwardly into the same, bolts disposed above the bed and extending transversely through and detachably connecting the portions of the holders and supports, above the bed, and the webs of the rails, and a transverse, metallic tie-rod disposed in and constituting a reinforcement for the transverse plastic bed portion and connecting the angle irons comprised in each holder and support and connecting the two holders and supports.

In testimony whereof I have hereunto set my hand in presence of two subscribing witnesses.

JOHN J. MARTIN.
